UNITED STATES PATENT OFFICE.

SVEN GUSTAF WIGELIUS, OF GOTTEBORG, SWEDEN.

INTERNAL-COMBUSTION ENGINE OF COMPOUND TYPE.

1,321,690.

Specification of Letters Patent. Patented Nov. 11, 1919.

Application filed March 8, 1918. Serial No. 221,216.

To all whom it may concern:

Be it known that I, SVEN GUSTAF WIGELIUS, subject of the King of Sweden, residing at Gottenborg, in the Kingdom of Sweden, have invented certain new and useful Improvements in Internal-Combustion Engines of Compound Type, of which the following is a specification.

The invention relates to internal combustion engines of the compound type, in which the high pressure piston acts as a valve for the low pressure cylinder, and in which the low pressure piston acts as a pump for scavenging the high pressure cylinder by the 10 two compartments of the low pressure cylinder being put into communication with each other through the high pressure cylinder. Internal combustion engines of this kind are previously known. The object of 20 the invention is generally to increase the efficiency of such engines while maintaining relatively small cylinder volumes. This is obtained by a cycle of operations one feature of which consists in the compression 25 produced in the low pressure cylinder during the last part of the return stroke of the low pressure piston and during the first part of the power stroke of the high pressure piston being carried so far that, when immediately afterward, the two cylinders are 30 put into communication with each other, there prevails a pressure on the low pressure cylinder, which is equal, or nearly so, to the pressure in the high pressure cylinder 35 at the time. This course of operation provides for a continuous expansion without losses due to momentary variations of pressure. To obtain the best possible efficiency the following expansion is to be carried 40 down to atmospheric pressure, but this would also require relatively large cylinder volumes. According to the present invention a small cylinder volume may be used by so adapting the relative movements of 45 the high and low pressure pistons that the working chamber of the low pressure cylinder is entirely closed up by the returning high pressure piston for a period immediately after the scavenging and before the 50 exhaust, thereby providing an after-expansion in the low pressure cylinder.

Thus, the essential features of the invention consists in the compression of the gases in the low pressure cylinder up to the pressure of the high pressure cylinder at the moment of opening the communication be-

tween the cylinders in combination with the provision of an after-expansion in the low pressure cylinder and the maintaining of a pressure above atmospheric pressure during 60 the scavenging period so as to obtain effective work out of the low pressure cylinder during the after-expansion.

A construction according to the invention is shown in the accompanying drawing in 65 which—

Figures 1, 2 and 3 show three positions of the pistons.

Another construction is shown in Figs. 4, 5 and 6.

For the sake of clearness, all the parts have, in the drawing, been placed in the same plane, although, in reality, the execution is different.

a is the high pressure cylinder, *b* the high pressure piston, *c* the low pressure cylinder, and *d* the low pressure piston. *e* is the air-valve of the high pressure cylinder chamber, *f* an inlet valve for fresh air to the chamber under the low pressure piston, and *g* an outlet valve from the said chamber. *h* is a channel connecting the two chambers, in which chambers there are arranged the valves *e* and *g*. *i* is a feeding valve for fuel, or for fuel and air.

The two cylinder chambers are in connection with each other by means of a port *k* in the wall between them, which port is so situated that those parts of the cylinder chambers that lie above the piston, come into communication with each other during the downward stroke of the high pressure piston *b*, at or approximately at, the same instant that the low pressure piston *d* turns in its upper position when the pressure in 95 the cylinders are equal, or almost so. On the other hand, the port *k* is so situated that a ring-shaped slot *l* in the high pressure piston *b* keeps the low pressure piston in connection with the outlet *m* during the greater part of the up-stroke of the low pressure piston rod, during which the blowing out takes place. The high pressure piston, during its down stroke, cuts off, however, the connection between the low pressure cylinder and outlet *m* by closing the opening *k* shown in the position illustrated in Fig. 2, after which compression takes place in the low pressure cylinder. During the continued downward stroke of the high pressure piston, and the up-stroke of the low pressure piston, the pressure in the low pres-

sure cylinder rises until it reaches the same, or approximately the same, value as the pressure in the high pressure cylinder, and the pistons are in the position shown in Fig. 3, when the communication between the two cylinders is brought about on the continued down stroke of the high pressure piston and the expansion takes place in both cylinders simultaneously.

10 In order to obtain the most suitable cooperation between the low pressure cylinder, on the one hand, and the outlet, or the high pressure cylinder, respectively, on the other, it is preferable to allow the pistons to assume such a relative position to each other that the high pressure piston has moved through a path corresponding to more than 90° but less than 180° before the low pressure piston begins its working stroke. When 15 each of the pistons is driven in the usual way by its own crank, the relative angle of the pistons to each other ought, consequently, to be greater than 90° but less than 180°, preferably 110°.

20 By this means there is obtained another advantage, viz., that the low pressure cylinder during the latter part of its down stroke, when the high pressure piston has already turned and is moving upward, sucks in scavenging air preferably introduced with a little over pressure, through the valve *e*, whereby an effective scavenging of the high pressure cylinder is obtained.

25 As, when the high pressure piston *b* moves upward, the low pressure piston *d*, which is larger, moves downward, and as the velocity of the last mentioned piston is considerably greater at that instant, the increase in volume in the low pressure cylinder is many times greater than the decrease in volume in the high pressure cylinder. The scavenging therefore continues during the continued upward movement of the high pressure piston *b* until this piston 30 has covered the port *h* after which compression takes place in the high pressure cylinder chamber until combustion begins. When this high pressure piston on moving upward covers the port *h*, the low pressure cylinder is at first entirely closed and as the low pressure piston is then still moving downward, a further expansion now takes place in the low pressure cylinder. This expansion continues until the high pressure piston again uncovers the port *h* when the low pressure cylinder is put in communication with the outlet channel *m*.

35 As is seen by the above description, the high pressure cylinder chamber never comes into direct communication, on any occasion, with the outlet channel *m*.

The scavenging air is obtained from the chamber under the piston *d*, where it is compressed to a suitable over pressure, after

which it is carried, during the scavenging 65 period, through the channel *h* and the valve *e* into the high pressure cylinder. In consequence of the inlet- and outlet ports for the scavenging air lying at opposite ends of the high pressure cylinder chamber, there is obtained a specially effective scavenging. The scavenging period does not begin, of course, until the pressure in the low pressure cylinder has fallen below the pressure of the scavenging air on the valve chamber of the 70 valve *e*.

In the embodiment shown in Figs. 4-6, the valves *f* and *g* are arranged in the upper part of the low pressure cylinder, and the port *h* in the lower part of the same. The 80 function is the same as that in the embodiment according to Figs. 1-3. The rate of speed of the movements of the respective pistons is, however, altered, as, in this form of construction, the low pressure piston 85 turns before the high pressure piston instead of after it, as in Figs. 1-3.

In the embodiment according to Figs. 4-6 the crank angle is—if ordinary crank movement is employed—180° greater than 90 in the embodiment according to Figs. 1-3, i. e., if, in Figs. 1-3 the high pressure crank goes 110° before the low pressure crank, the high pressure crank in Figs. 4-6 goes 290° before the low pressure crank, 95 or, otherwise expressed, 70° after the same.

The advantage of the embodiment according to Figs. 4-6 is that the channel *h* is considerably shorter than in the embodiment according to Figs. 1-3.

100 I claim:

Method of working internal combustion engines of the compound type, in which the high pressure piston acts as a valve for the low pressure cylinder, consisting in compressing the gases in the low pressure piston during the last part of the return stroke of the low pressure piston and during the first part of the power stroke of the high pressure piston; carrying said compression so far that when, immediately afterward the two cylinders are put into communication with each other, there prevails a pressure in the low pressure cylinder, which is equal, or nearly so, to the pressure in the high pressure cylinder at the time; producing an expansion of the combustion gases in both cylinders; scavenging the high pressure cylinder by putting the two compartments of the low pressure cylinder into communication with each other through the high pressure cylinder; maintaining a pressure above the atmosphere in both cylinders during the scavenging operation; closing the working chamber of the low pressure cylinder by the returning high pressure piston, while the low pressure piston is still moving outward, producing an expansion in said chamber.

ber, connecting said chamber with the exhaust port through an opening in the high pressure piston, and maintaining the exhaust from the low pressure cylinder until 5 the high pressure piston after having performed part of its power stroke again closes the low pressure cylinder, at which moment the compression in the low pres-

sure cylinder is started and the cycle of operations is repeated.

In testimony whereof I affix my signature 10 in presence of two witnesses.

SVEN GUSTAF WIGELIUS.
